(57) **CLAIM**

The ornamental design for a motor vehicle, as shown and described.

DESCRIPTION

FIG. 1 is a top, front and side perspective view of a motor vehicle showing our new design;

FIG. 2 is a front and side perspective view thereof;

FIG. 3 is a rear, front and side perspective view thereof;

FIG. 4 is a right side view thereof;

FIG. 5 is a front view thereof;

FIG. 6 is a top view thereof;

FIG. 7 is an enlarged elevational view of part A taken along line 7-7 end in FIG. 4;

FIG. 8 is an enlarged elevational view of part B taken along line 8-8 end in FIG. 4;

FIG. 9 is an enlarged elevational view of part C taken along line 9-9 end in FIG. 4; and,

FIG. 10 is an enlarged elevational view of part D taken along line 10-10 end in FIG. 4.

The claim for a motor vehicle shown in FIGS. 1-6 is shown within the broken lines and the broken lines and any element shown outside the broken lines form no part of the claimed design, but instead are included to show environmental aspects of the claimed design. The broken lines shown in FIGS. 7-10 of an inner portion of the motor vehicle are for the purpose of illustrating subject matter that forms no part of the claimed design.
